J. OLIVER.

SUPPORT FOR TRANSMISSION CASINGS FOR AUTOMOBILES.

APPLICATION FILED SEPT. 11, 1915.

1,209,877.

Patented Dec. 26, 1916.

UNITED STATES PATENT OFFICE.

JOHN OLIVER, OF EKALAKA, MONTANA, ASSIGNEE OF ONE-HALF TO JOHN W. HATTON
AND ONE-HALF TO WILLIAM MOWBRAY, BOTH OF EKALAKA, MONTANA.

SUPPORT FOR TRANSMISSION-CASINGS FOR AUTOMOBILES.

1,209,877.

Specification of Letters Patent. Patented Dec. 26, 1916.

Application filed September 11, 1915. Serial No. 50,275.

To all whom it may concern:

Be it known that I, JOHN OLIVER, a citizen of the United States, residing at Ekalaka, in the county of Fallon and State of 5 Montana, have invented certain new and useful Improvements in Supports for Transmission-Casings for Automobiles; and I do hereby declare the following to be a full, clear, and exact description of the invention, 10 such as will enable others skilled in the art to which it appertains to make and use the same.

This invention relates to new and useful improvements in supports for transmission 15 casing for automobiles, and the principal object of the device is to provide a means for supporting the transmission and crank casing temporarily during the assembling of the vehicle.

20 Another object of the invention is to provide a device which is readily attachable to motor vehicles in order to provide an auxiliary support in case of breakage of any of the parts in order to prevent the motor from 25 dropping and coming out of alinement.

Still another object of the invention is to provide a device which is readily adjustable to different sized motors, and which is so arranged that one side may be raised or lowered with relation to the other side.

With these and other objects in view, the invention consists in the novel combination and arrangement of parts which will be fully set forth in the following specification 35 and accompanying drawings, in which:—

Figure 1 is a view illustrating this improved device in use, Fig. 2 is a perspective view of the invention, Fig. 3 is a sectional view through the supporting plate, 40 Fig. 4 is a sectional view through one of the adjusting plates.

Referring now to the drawings by characters of reference, the numeral 1 designates as an entirety, a motor of the ordinary construction, provided with the usual cylinders 45 2 and crank casing 3. This crank casing 3 is formed with an enlargement in which the flywheel is rotatable, and the attachment is shown in Fig. 1, as it would appear when in use in connection with the crank casing.

The chassis of the vehicle is designated by 50 the numeral 4, and it will be apparent that the attachment is suspended, as illustrated, to support the motor temporarily during 55 the proper alining of the propeller shaft

with the crank shaft, designated by the numeral 5.

The attachment above referred to comprises the plate or disk 6 provided with a central opening 7 for the accommodation 60 of the usual pet cock located in the underside of the flywheel casing, and this plate 6 is provided with the opposite ears 8 through which the eyes 9 of the rods 10 extend. The upper ends of these rods are 65 threaded, as at 11, and project through an opening formed in the hanger plate, which will be more fully hereinafter described. A nut 12 is threaded on the upper end of each rod and engages the upper side of the 70 hanger plate, as clearly shown in the drawings.

The hanger plate above referred to is designated generally by the numeral 13 and comprises the oval body 14 provided with 75 a central opening through which the upper end of the rods 10 extend, and formed integral with opposite ends of the body are the standards 15 provided at their upper ends with the hooks 16 which engage the 80 chassis, as shown in Fig. 1, and form a support for the whole. It is to be understood that suitable cushioning material may be secured to the upper side of the plate 6 in order to avoid injuring the under side of the 85 crank casing.

It will be apparent from the foregoing that in use, should any portion of the motor become disconnected from the chassis of the vehicle, and should drop out of alinement, 90 the attachment may be put in place by adjusting the plate to the proper height by means of the nuts 12 and the rods 10, and the hooks 16 may be placed over the side bars of the chassis, and it will thus be seen 95 that the device will be supported in such a position as to hold the motor and the propeller shaft in proper alinement for operation.

While in the foregoing there has been 100 shown and described the preferred embodiment of this invention, it is to be understood that such changes may be made in the combination and arrangement of parts as will fall within the spirit and scope of the 105 appended claims.

What is claimed is:—

1. A device of the character described comprising a supporting disk for the crank case of a motor vehicle, rods extending up- 110

wardly from the crank case supporting member, U-shaped hangers on the upper ends of the rods adapted to engage the side bars of the chassis of a motor vehicle, and means 5 to adjustably secure the rods on the arms of the hangers to permit the device to be used with a different sized motor.

2. A device of the character described comprising a disk provided with a central 10 opening, apertured ears formed at diametrically opposite points on the periphery thereof, rods swivelly connected to the ears and extending upwardly therefrom, threads on the upper ends of the rods, U-shaped hanger plates fitted 15 on the threaded ends of said rods, said hanger plates provided with a central opening, a nut on the rods adjustably holding the same in position on the hanger plates, and a hook on the opposite ends of the arms of the 20 hanger plate to engage the side bars of the chassis of a motor vehicle.

3. A device of the character described

comprising a disk, ears formed at diametrically opposite points on the periphery of the disk and extending laterally therefrom 25 and in the same plane thereof, rods swivelly connected to the ears and extending upwardly therefrom, threads on the upper ends of the rods, U-shaped hanger plates fitted 30 on the threaded ends of said rods, said hanger plates provided with central openings, a nut on the rods adjustably holding the same in position on the hanger plates, and hooks on the opposite ends of the arms 35 of the hanger plates to engage the side bars of the chassis of a motor vehicle for steady-ing the same.

In testimony whereof I affix my signature in presence of two witnesses.

JOHN OLIVER.

Witnesses:

S. M. BAIRD,

W. L. MAHNKEN.
